FIRECRACKER PACKAGE

Robert B. Whiteside, Los Angeles, Calif.

Application March 31, 1937, Serial No. 134,073

2 Claims. (Cl. 102—22)

This invention is a firecracker package combination.

An object of the invention is to provide a package of loose or free firecrackers in which the 5 crackers are packed in parallel rows in a common plane with the crackers arranged transversely in their rows and preferably with their fuses all disposed at the inner ends of the crackers, that is, fuse ends in juxtaposition, all of the crackers 10 being entirely unattached in any manner in the pack. Thus the loose crackers may be handled one at a time without any unbraiding or breaking of other fastening means sometimes provided to fix the arranged crackers in the pack.

15 By arrangement of the crackers with their fuses in juxtaposition the whole pack may be fired at once if so desired.

A further object is to provide a container or 20 box structure preferably of one piece of material for confining the crackers in their row plane against dislodgement and to provide for ready access to the fuses for purpose of igniting the pack as a whole.

Also, an object is to provide a package containing a match-headed, slow burning, fuse lighting 25 element or stick serving to stiffen the package, and provide a closure incorporating a match strike.

The invention consists of certain advancements 30 in this art as set forth in the ensuing disclosure and having, with the above, additional objects and advantages as hereinafter developed, and whose construction, combination and details of means, and the method and the manner of 35 operation will be made manifest in the description of the annexed, illustrative embodiment; it being understood that modifications, variations and adaptations may be resorted to within the scope, principle and spirit of the invention as it 40 is more directly claimed in the appendage.

Figure 1 is a perspective of a partially closed, preferred form of the package. Figure 2 is a perspective of the frontal or window side of the sealed pack. Figure 3 is an edge and back perspective thereof. Figure 4 is a sectional elevation of the match stick. Figure 5 shows the scheme of laying the loose fuses in between the rows of crackers.

Figure 6 is a plan of a strip blank, Figure 7 is 50 a perspective of a partly folded box, and Figure 8 is a perspective of a packed and sealed package of a modified form of the invention.

Figs. 1 to 3 inclusive, show a package in which 55 two rows 2 and 3 of crackers C are laid in a plane with their fuses 4 all disposed at the inner ends

of the crackers; these being laid transversely in their respective rows.

The fuses 4 are all laid parallel in one direction toward one end of the rows of crackers and toward a narrow slit 5 provided in one of the 5 four side walls 6 of a shallow container or envelope, Fig. 3. The fuses of the endmost crackers are bent to line along the wall 6 in which the slit 5 is provided at a position such that by inserting a fingernail the user may slightly tear 10 open the wall to pull out a portion of a near fuse to be lighted for firing the whole pack at one time by reason of running of the fire along the fuses at the center of the pack at the inner ends of the rows of crackers. 15

The envelope E is formed of a single piece of paper in blank having a frontal panel 10 of frame form providing a window 11. The four sides of the panel 10 are foldably joined by the respective, four walls 6, which have a width determined 20 by the number of layers of rows of crackers to be packed. The sides or walls 6 stand upright as to the window panel 10.

A narrow flap 13 along one wall 6 is adapted 25 to be folded inward over the laid crackers. Opposite to the flap 13 is a parallel, full size cover leaf 14 the outer face of which provides for direct imprint of a label on face L, Fig. 3.

The walls 6 which are transverse to the cover leaf 14 have infolding, reinforcing flaps 15 preferably as wide as their basal walls 6 and long enough to well overlap each other, Fig. 1, whereby to form with the leaf 14, triple plies of the paper stock to stiffen the envelope and keep the rows of crackers in plane. 35

When the package is made up as in Fig. 1, it is only necessary to apply paste to narrow zones a—b—c along the cover leaf 14 and stick this down on the adjacent margins of the flaps 15 and flap 13. 40

The package includes, if desired, a stiff, slow burning stick or element 17 laid between contiguous fuse-ends of the rows 2 and 3 of crackers. The stick is preferably made of a piece of perfumed, rolled, slow-burning paper to form an 45 empty tube the centric hole 18 of which provides an airway to aid combustion. To further the purpose of an all-in-one firecracker package the tubular stick 17 is provided with a matchhead 19 having a stem 20 set in one end of the tube 50 in suitable manner, though the combustible head may be otherwise produced on the stick.

The envelope has at a suitable location, as on a wall 6 remote from the cracker fuses, an abrasive match strike 21. Thus the stick 17 may be ex- 55

tracted from the pack and lighted by rasping its head 19 on the strike 21. As soon as the stick glows the user may proceed to open the package for extracting individual crackers or ignite the near fuse at slit 5.

5 The container or envelope E may be of any desired material and if the window be in the form of an opening if desired it may be covered with a transparent sheet 11a.

10 The window 11 may be formed in the panel as by impregnating the stock with an oily substance, in well known manner.

15 In Figs. 6 to 8 is shown a box structure including a blank having a narrow backbone strip 25 and along opposite sides is a pair of equal, short flaps 26-27, at one end, next to longer, opposite equal flaps 28-29 separated from flaps 26-27 by slits 30 which extend to the center strip 25. Next to and cut free of the flaps 28-29 20 are opposite short flaps 31-32 of the same length as flaps 26-27, and at the opposite end of the strip 25 are opposite flaps 33-34 cut free of the near ends of flaps 31-32 and being as long as flaps 28-29.

25 Weakened or perforated lines 35 along the strip 25 provide for accurate, ready bending of the flaps into a channel or box forming position, Figs. 7 and 8. Bending the strip 25 to form a rectangular frame, Fig. 7, brings the infolded flaps 26-28-31-33 into co-planar, bottom forming relation with overlapping end zones which are pasted in an obvious manner and thus 30 form an open window W.

35 Rows of firecrackers C are now laid along the bottom of the open box, Fig. 7, and a match stick 17 is packed between adjacent or inner ends of

the crackers. The short flaps 27 and 32 are folded in and down on the contents and the longer, parallel top flaps 29-34 are folded down and pasted where they overlap the lower flaps 27-32; thus forming a top window W', Fig. 8.

5 The window openings W-W' are covered by a transparent sheet 36 which may encase the whole pack as shown in Fig. 8. The exposed surfaces of the several flaps of this pack provide effective display area for suitable printed matter.

10 The fuses of the crackers in the box of Fig. 8 are loosely laid along the inner edges of the opposed rows, of crackers, 2 and 3 and contiguous fuses 4 are clustered along the tearing aperture 37 to enable lighting off the full pack if desired.

15 Zones 38 of adhesive on the inside face of panel 10, Fig. 5, provide for attachment directly to the cover itself, if desired, of the crackers C.

What is claimed is:

1. A firecracker package having an unstable envelope of pliant, tearable material such as used for wrapping firecrackers, a flat assembly of firecrackers packed therein, and an elongate, bar-like device of non-metallic material stiffer than the envelope and of a length not greater than 25 that of the walls of the envelope to which it is parallel and which reinforces or stabilizes the package in directions transverse to the length of said device; said device being of such cross-sectional shape as not to overlap the periphery of 30 contiguous ends of firecrackers.

2. A firecracker package as in claim 1, and in which the stabilizing device is wholly unattached in the package.

ROBERT B. WHITESIDE. 35
